Patented Jan. 13, 1925.

UNITED STATES PATENT OFFICE.

HENRY D. BOKOP, OF DEFIANCE, OHIO.

RECEPTACLE.

Application filed April 11, 1924. Serial No. 705,789.

To all whom it may concern:

Be it known that I, HENRY D. BOKOP, a citizen of the United States, and a resident of Defiance, in the county of Defiance and State of Ohio, have invented a new and useful Receptacle, which invention is fully set forth in the following specification.

This invention relates to packaging receptacles, and particularly to packing crates, firkins, barrels or the like having encircling bands or hoops and removable closures at one or both ends thereof.

An object of the invention is the provision in combination with an embracing band and a removable end closure of a device of the class described, all members adapted to encircle portions of the band or hoop and having projecting end portions bendable over the adjacent end portions of the closure for nailing thereto to prevent removal of the closure.

A further object of the invention is the provision in devices of the class described of a built up or fabricated hoop or band construction having means for uniting or tying the end portions of a hoop or band together and at the same time serving to secure an end closure in position.

The invention is fully described in the following specification, and while in its broader aspect it is capable of embodiment in numerous forms, a preferred embodiment thereof is illustrated in the accompanying drawings, in which,

Figure 1 is an end view of a receptacle embodying the invention, with parts broken away, and with a portion of the closure securing members disengaged therefrom. Fig. 2 is a side elevation thereof with all of the closure holding members in engaging position. Figs. 3 and 4 are sections respectively on the lines 3-3 and 4-4 in Fig. 1.

Referring to the drawings, 1 designates the body of the receptacle, which body, in the present instance, is of circular form and provided at its upper and lower edges with reinforcing encircling bands or hoops 2. One or both ends of the receptacle may be closed by removable closure members 3 of any suitable form. These closure members preferably seat down in the open ends of the receptacle and have cross-pieces 4 at their outer sides adapted to have their ends lap the adjacent end edges of the

device to limit the extent of insertion of the closure members therein.

The hoops 2, for cheapness of construction and for the purpose of utilizing small strips or bands of wood, are preferably composed of two or more bands, disposed one within the other, and these bands are preferably built up from short sections which are placed end to end. The band sections in the present instance are semi-circular in form, two being required for each band. The inner band 2^a has the abutting ends of its members secured together at the inner sides thereof by sheet metal strips 5, the inner ends of which are disposed between the body 1 of the device and the band 2^a in bridging relation to the abutting ends of the members of the band and being secured thereto by nailing, or in any other suitable manner. The outer ends of these bands are of sufficient length to extend down under the inner edge of the hoop and thence outwardly around the hoop and over the adjacent end of an edge lapping portion 4 of the adjacent closure 3, being nailed thereto to serve to retain the closure in engagement with the body of the receptacle.

These strips are nailed or otherwise secured at their inner ends to the outer sides of the band 2^b in bridging relation to the respective joints thereof and with the outer free ends of the strips extending outwardly from the hoop longitudinally of the packaging device and away from its center. The band is then wrapped around the hoop over the top and down at the inner side thereof and thence outwardly under the lower edge of the hoop, and the free end of the strip is of sufficient length to be drawn up around the outer side of the hoop and in lapping relation over the adjacent edge portions of the closure parts 4 to which they are secured by nailing, or in any other suitable manner.

For the purpose of further strengthening the hoop, the ends of the inner band 2^a may be joined together at their outer sides by sheet metal strips 7 disposed between the bands 2^a and 2^b.

By my invention I am not only able to utilize small strips of material in the building up of a fabricated hoop construction, but I also utilize the reinforcing or tying members for the strips or sections of the

hoop to secure the closure members of the receptacle in position.

It is evident that the hoop is built up and the strips 5 and 6 attached thereto before the hoop is secured to the body of the receptacle, so that a hoop and the securing means for an adjacent closure member constitutes a single unit. It is also evident that the strips 5 and 6 in addition to serving as closure securing means materially reinforce and strengthen the hoop and make it possible to produce a cheap fabricated hoop construction.

I wish it understood that my invention is not limited to any specific construction, arrangement, or form of the parts, as it is capable of numerous modifications and changes without departing from the spirit of the claims.

Having thus described my invention what I claim as new and desire to secure by Letters Patent, is,—

1. In a receptacle, a hoop of fabricated construction and bendable strips embracing portions of the hoops to secure the fabrications thereof together, and having free end portions extending therefrom and adapted to engage over and be secured to an associated closure member to retain it to the receptacle.

2. In a receptacle, a hoop of fabricated construction having bendable strips wrapped around the hoop in embracing reinforcing relation to the joints of the fabricated structure and having free end portions extending from the hoop and adapted to be bent over and secured to a closure member of the receptacle.

3. In a receptacle, a hoop having inner and outer bands, the inner band being formed of end abutting sections, bendable strips secured to the sections of the inner band in bridging relation to the joints there-

of, and thence extending outwardly from the hoop under the inner edge thereof and 45 adapted to have its free end portion bent around the outer side of the hoop and in securing relation over a portion of an end closure member of the receptacle.

4. In a receptacle, a hoop comprising a 50 plurality of bands, one without the other, the outer band being formed of end abutting sections, and bendable strips having one end portion secured to the outer side of the outer band in bridging relation to the joints of its 55 section and thence extending around the hoop, and having a free end portion projecting from the inner edge of the hoop and adapted to be bent across the outer side of the hoop and over adjacent portions of an 60 end closure member in securing relation thereto.

5. A receptacle comprising a drum-like body, an enclosure for the body having edge portions lapping the body end, a hoop on the 65 body and bendable strips each secured at one end to the hoop and thence wrapping around the hoop and having free end portions which are bendable over the adjacent edge portion of the closure member in securing relation 70 thereto.

6. A receptacle comprising a drum-like body, an enclosure for the body having edge portions lapping the body end, a fabricated 75 hoop composed of a plurality of bands, each having several end abutting sections, and bendable strips secured to the hoop in engagement with respective bands and in bridging relation to the respective ties thereof, and having their outer end portions projecting from the hoop and free for bending over adjacent edge portions of the closure member in securing relation thereto.

In testimony whereof, I have hereunto signed my name to this specification.

HENRY D. BOKOP.
